UNITED STATES PATENT OFFICE.

PAUL MOHRMANN, OF CHICAGO, ILLINOIS, ASSIGNOR TO FRIELEY VOSHARDT CO., OF CHICAGO, ILLINOIS, A CORPORATION OF ILLINOIS.

DESIGN FOR A RING FOR SUPPORTING GLASS LIGHTING-BOWLS.

49,193.

Specification for Design.

Patented June 13, 1916.

Application filed February 16, 1916. Serial No. 78,768. Term of patent 7 years.

To all whom it may concern:

Be it known that I, PAUL MOHRMANN, a citizen of the United States, residing at Chicago, in the county of Cook and State of Illinois, have invented a new, original, and ornamental Design for a Ring for Supporting Glass Lighting-Bowls, of which the following is a specification, reference being had to the accompanying drawing, forming part thereof.

Figure 1 is a side elevation of a ring for supporting glass lighting bowls, showing my new design. Fig. 2 is a top or plan view of the same.

I claim:

The ornamental design for a ring for supporting glass lighting bowls, as shown.

PAUL MOHRMANN.
